 6 Claims. (Cl. 340—347)

This invention relates in general to translators and in particular to two-access translators in which one access can be used as an inlet and the other access as an outlet, and vice versa.

In present day telephony, for example, it is customary to represent the decimal digits according to a code called "two-out-of-five," in which each digit is characterized by the marking of two elements out of five. For example, a connection to ground of two wires in a group of five, the energization of two relays, etc. . . . The two-out-of-five code supplies at least ten combinations which characterize the ten decimal digits. Also, the noted code can be checked since it is easy to verify that two digits at least, and only two of the elements of a group of five are marked, the other combinations being considered erroneous.

The assignment of the combinations of the "two-out-of-five" code to the decimal digits may be arbitrary. However, standardization resulted in two codes have mainly been used up to now for translating the decimal digits. Both are based upon the "weighting" of the elements of the code.

In the first code, the elements have been assigned values 1, 2, 4, 8, 0, respectively. The translation of the decimal digits is effected according to the following table.

1=1+0
2=2+0
3=1+2
4=4+0
5=1+4
6=2+4
7=4+8
8=8+0
9=1+8
0=2+8

It should be noted that in the rule for the establishment of the combinations is logical except for the digit 7 being translated by 4+8.

In the second code, the elements have been assigned the values 0, 1, 2, 4, 7, respectively. The translation of the decimal digits is effected according to the following table:

1=0+1
2=0+2
3=1+2
4=0+4
5=1+4
6=2+4
7=0+7
8=1+7
9=2+7
0=4+7

This time, the exception is the digit 0 which is translated by the combination 4+7.

It should be noted that in both codes, the combinations translating the digits 1 to 6 utilize the elements with the same "weights." On the other hand, the combinations translating the digits 7 to 0 include an element "8" or "7," according to the code. It thus follows that an alter-

ation of the combinations must be effected in order to make a direct changeover from one code to the other.

The present invention concerns a simple device which translates the two-out-of-five code "1, 2, 4, 8, 0" into a two-out-of-five code "0, 1, 2, 4, 7" and reversely. This invention is concerned more generally with the translation of a weighted code into another weighted code having the same number of elements, when the "weight" of one or more elements is different in both codes.

10 One feature of the invention relates to a two-access translating device, one access being used as an inlet and the other as an outlet, and vice versa. The inventive device mainly includes a three-position detecting circuit which assumes a first position when no combination is applied to the device, at which time the two accesses are isolated from each other; a second position when a combination applied to one of the accesses is composed of elements having the same "weights" in both codes, at which time the detecting circuit connects the marked conductors of one access to the same conductors in the other access; and a third position when a combination applied to one of the accesses includes one at least of the elements the "weight" of which is different in both codes, at which time the detecting circuit connects the conductors of the two accesses two by two, according to a law given by this difference of "weight."

Another feature of the invention relates to a detecting circuit composed of two relays which circuit can assume three positions. In position one, when there is no code, both relays remain at rest. In position two, when on either access, a combination which only includes the elements having the same "weight" in both codes, is received, a first relay is energized and a second relay is at rest. In position three, when on either access, a combination which includes the element the "weight" of which is different in both codes is received, a first relay is at rest and a second relay is energized.

Another feature of the invention relates to the fact that the first relay includes two winding wires in opposition, such that the reception of the elements having the same "weights" in both codes, energizes one of said windings, and the reception of the element having a different "weight" in both codes energizes the other winding, so that the first relay is energized only if the received combination includes elements having the same "weight" only.

Another feature of the invention relates to the fact that the second relay is connected in parallel with the second winding of the first relay, so that it is energized when the first relay subjected to the influence of opposite fluxes produced simultaneously in its two windings, remains at rest.

Various further features will be disclosed from the following description which is given by way of non-limited examples, and with reference to the accompanying drawing which represents a translating device in conformity with the present invention.

The translating device includes two accesses C and D. The five wires of access C receive the digits translated according to code "1, 2, 4, 8, 0," the elements of which are applied respectively by connecting ground to wires C1, C2, C4, C8, C0. According to the invention these digits must be retransmitted over access D, in code form "0, 1, 2, 4, 7," the elements of which are applied respectively by connecting ground to wires D0, D1, D2, D4, D7.

65 Reciprocally, a digit received in code "0, 1, 2, 4, 7" over the conductors in access D is retransmitted in code "1, 2, 4, 8, 0" over the conductors in access C.

70 The transfer of a combination from one access to the other is accomplished by means of relays A and B. Relay A includes two windings operating in opposite direction, such that relay A remains at rest if both of its windings are energized simultaneously.

The negative current-supply battery is not represented. The circuits leading to said battery are ended by an arrow.

The left-hand winding of relay A is connected, by diodes dc_1 , dc_2 , dc_4 , dc_0 , dd_1 , dd_2 , dd_4 , to the wires corresponding to the elements common to the two codes which are of weights 0, 1, 2, 4. The right-hand winding of relay A and relay B are connected, by diodes dc_8 and dd_7 , to the wires corresponding to the 8-“weight” element of code “1, 2, 4, 8, 0” and to the 7-“weight” element of code “0, 1, 2, 4, 7.”

The presence of the diodes avoids mixing the code wires and enables the two accesses to be maintained isolated from each other when both relays are at rest.

When a combination 0 received on either access, includes 0-1-2-4-“weight” elements only, relay B remains at rest and only the left-hand winding of relay A is current-supplied. By way of example, when the combinations 2+4 is received, which indicates the digit 6 by connecting wires c_2 and c_4 to ground. The left-hand winding of relay A is current-supplied through diodes dc_2 and dc_4 and relay A operates.

The closure of contacts a_1 , a_2 , a_4 and a_0 connects wires C_1 , C_2 , C_4 , C_0 to wires D_1 , D_2 , D_4 , D_0 , respectively. The continuity of the 0-1-2-4-“weight” wires ensures the transfer of the combination received from one access to the other, in each direction. More particularly, wires D_2 and D_4 connect to wires C_2 and C_4 and combination 2+4 is retransmitted over access D.

If, through access C, the device receives a combination such as 0+8 by grounding wires C_8 and C_0 , the left-hand winding of relay A is current-supplied through diode dc_0 , whereas the right-hand winding of the same relay is current-supplied simultaneously through diode dc_8 . The fluxes produced by both of these windings are balanced and relay A remains at rest. On the other hand, relay B connected in parallel with the right-hand winding of relay A is operated.

The closure of contact $b_8.7$ connects wires C_8 and D_7 .

The closure of contacts $b_{1.2}$, $b_{2.4}$, $b_{4.a}$, $b_{0.1}$, connects wires C_1 , C_2 , C_4 , C_0 to wires D_2 , D_4 , D_0 , D_1 , respectively, thereby translating the combinations 1+8 into 2+7, 2+8 into 4+7, 4+8 into 0+7, and 0+8 into 1+7.

The combination received which marks the wires C_0 and C_8 of access C, is retransmitted therefore over access D by the marking of wires D_1 and D_7 , i.e., under the combination 1+7.

The operation is the same should combination 1+7 be received on access D. The left-hand winding of relay A is current-supplied through diode dd_1 and its right-hand winding is current-supplied through diode dd_7 . Under these conditions, relay A remains at rest whereas relay B energizes. The same connections being established, wire D_7 is connected to wires C_8 , and wire D_1 is connected to wire C_0 , which results in the translation 1+7=0+8.

It is clear that the preceding description has only been given as an unrestrictive example and that numerous alternatives may be considered without departing from the scope of the invention. By way of example, the codes could be different, either by the number of elements or by the weighting. Also, electronic elements could be used instead of relays.

I claim:

1. A bi-directional translator for translating multi-element codes of a first coding system into multi-element

codes of a second coding system and for effecting the reverse translation thereof, the elements of each coding system having respective weights assigned thereto with the correspondence between the weights of the two systems being assigned in accordance with a predetermined formula, a first and a second access for respective coding systems each having an ordered set of terminals corresponding respectively to the elements of its respective system, and detecting means common to both said accesses for controlling connections between the terminals of either access and the terminals of the other access in accordance with said predetermined formula to enable correct translations from the first access to the second access and from the second access to the first, said detecting means comprising a combination of two relays operable responsive to any marking appearing on any terminal of either access.

2. A bi-directional translator for translating multi-element codes of a first coding system into multi-element codes of a second coding system and for effecting the reverse translation thereof, the elements of each coding system having respective weights assigned thereto with the correspondence between the weights of the two systems being assigned in accordance with a predetermined formula, a first and a second access for respective coding systems each having an ordered set of terminals corresponding respectively to the elements of its respective system, said accesses comprising a combination of two relays operable responsive to any marking appearing on any terminal of either access.

3. A bi-directional translator as set forth in claim 2 wherein the four of the elements of the codes of one system have identical weights assigned to a respectively corresponding four of the elements of the codes of the other system.

4. A bi-directional translator as set forth in claim 3 wherein the said detecting means comprises a three position device having positions indicative of both elements of both codes being identical, indicative of one element of each code being identical and one element of each code being different, and indicative of both elements of both codes being different.

5. A bi-directional translator as set forth in claim 2 wherein said detecting means comprises a combination of two relays operable responsive to any marking appearing on any terminal of either access.

6. A bi-directional translator as set forth in claim 5 wherein the said relay combinations are connected to all the terminals of said accesses through uni-directional current devices.
